(57) **CLAIM**

The ornamental design for an AC charging pile as shown and described.

DESCRIPTION

The patent or application file contains at least one drawing executed in color. Copies of this patent or patent application publication with color drawing(s) will be provided by the Office upon request and payment of the necessary fee.

1. AC charing pile

1.1 : Front

1.2 : Back

1.3 : Left

1.4 : Right

1.5 : Top

1.6 : Bottom

1.7 : Perspective

No claim is made for color shown on the reproductions. The broken lines shown in the drawings are for the purpose of illustrating portions of the AC charging pile that form no part of the claimed design.

1 Claim, 7 Drawing Sheets
